UNITED STATES PATENT OFFICE

GEORGE A. RICHTER, OF BERLIN, NEW HAMPSHIRE, ASSIGNOR TO BROWN COMPANY,
OF BERLIN, NEW HAMPSHIRE, A CORPORATION OF MAINE

METHOD OF DECOLORIZING CAUSTIC LIQUORS

No Drawing.

Application filed February 13, 1928. Serial No. 254,166.

This invention relates to the decolorization of caustic liquors, and more particularly to highly concentrated liquors such as are known on the market as "liquid caustic", and consist of aqueous solutions of caustic soda of about 50%, more or less, caustic soda concentration. Caustic liquors of this character are likely to have a characteristic cloudy, bluish-gray appearance, as a result of impurities contained therein. These impurities probably either originate in the sodium chloride used as a raw material in the manufacture of the liquor, or are formed or picked up in the processing apparatus, for instance in the evaporators, pipes, and tanks, and appear in the resulting liquor in a colloidal condition, for example in the form of silicious matter, sodium ferrate, or other colored colloidal compounds. When the liquors are employed in the arts, for example in the rayon or textile industry, the sodium ferrate or other impurities are objectionable, as they are liable to cause undesirable coloration or otherwise impair the quality of a product.

It has heretofore been difficult to remove the impurities from caustic liquors. Thus, textile filter cloths cannot withstand the chemical action of these liquors, while the usual wire cloths are of insufficiently close weave to permit filtering them out. It is difficult to separate much of these impurities by settling, as they will not settle, and if their removal is attempted by passing the liquor through solid filtering mediums such as sand, it is found that the liquor undergoes reaction therewith.

I have discovered that if caustic liquors of the character described are contacted with cellulose fibers in an unwoven, loose or random condition, and consisting substantially only of alpha cellulose, the colored colloidal impurities contained therein are largely removed without deleteriously affecting the liquor. Undoubtedly the fiber adsorbs the impurities on its surface, and, owing to its inert character undergoes practically no reaction with the liquor other than being mercerized thereby.

In successfully practising the process of the present invention, it is essential to employ

fiber consisting substantially only of alpha cellulose, for should the fiber contain non-alpha cellulose components even in amount such as present in ordinary papermaking pulps such as sulphite, it would be quite unsatisfactory for use in decolorizing caustic liquor, for the reason that the ligneous matter, less-resistant celluloses, oxycelluloses, and other non-alpha cellulose components present in sulphite pulp would react with the liquor, not only producing colored reaction products, but consuming caustic soda in the process.

A fiber consisting substantially only of alpha cellulose such as I employed, may be produced, for instance, by refining a wood fiber, for instance,—that is, removing its non-alpha cellulose components. For example, a raw pulp such as unbleached sulphite may be refined by digesting such pulp in caustic soda or other alkaline solution, and then bleaching the digested product. The refining of such pulp may be facilitated by treating the raw pulp with a relatively weak oxidizing reagent, such as chlorine water, before alkaline digestion. The pulp resulting from the refining treatment is a highly adsorptive product of high alpha cellulose content, which does not react with or color caustic soda liquor. In lieu of a refined wood pulp, I may employ a good grade of cotton fiber, preferably fiber which has been subjected to alkaline digestion for the removal of waxes, fats, and other impurities which may form colored reaction products with the caustic liquor. The fiber may be used in any suitable condition, it being preferable to beat or fray the fibers so as to increase their adsorptive surface. The beating should not be carried to excess, that is, to a point where the fiber becomes markedly gelatinized, as this tends to depolymerize the cellulose and increase its reactivity with caustic liquor. The present invention will now be described for the purpose of illustration as applied in decolorizing caustic liquor produced by the electrolytic process, it being understood that the present invention is also applicable to caustic liquors produced by other processes. In the manufacture of caustic soda by the electrolytic

process, it is the practice to electrolyze a solution of sodium chloride in suitable electrolytic cells, to bleed off the dilute caustic soda solution being formed at the cathode compartments of the cells and to deliver it into evaporating apparatus, for instance of the multiple-effect type. The caustic soda solution thus formed contains substantial amounts of unelectrolyzed sodium chloride, but when the solution is concentrated in the evaporators, the sodium chloride is precipitated, while the more highly soluble caustic soda remains in solution. If this concentration is carried out to a point where solid caustic soda is produced, not only is the sodium chloride precipitated, but also colored colloidal impurities such as iron compounds; but if the concentrating operation is carried out to yield "liquid caustic" or caustic liquor, such as the present invention deals with, colloidal coloring impurities and fine particles of unelectrolyzed salt are likely to remain in the liquor. In accordance with the present invention, the caustic liquor thus produced is contacted with fiber composed substantially only of alpha cellulose, as previously described. Contact between the fiber and the liquor may be effected as by mixing the liquor and the fiber, and then removing the fiber, or by passing the liquor through one or more masses of the fiber. Thus the liquor may be delivered from the evaporators into agitating tanks, and dry fiber in a shredded or a fluffed condition resembling cotton linters added and mixed therewith. Fiber in a suitable fluffed condition may, for instance, be produced as by rasping the surface of a relatively thick sheet of such fiber in a form known in the pulp industry as "drier sheet," for instance, with wire brushes. About 1% of fiber based on liquor, when intimately mixed with the liquor for a few minutes, effects a substantially complete adsorption or removal of the impurities from the liquor. The decolorizing operation may be carried out at room temperature conditions, but if desired the liquor may be delivered from the evaporating apparatus into the agitating tanks while still warm, say, at a temperature of 40° C., or higher, for even under these conditions, other than mercerization there is practically no reaction between the fiber and the liquor. The fiber suspended in the liquor after the decolorizing operation may be removed as by passing the liquor through a rotary filter designed to prevent passage of the fiber therethrough, the passing of the liquor through the filter being facilitated if the liquor is at elevated temperature, as previously described. As the liquor passes through the filter, a mass of fiber accumulates on the filter, which serves to catch fine mechanical impurities such as the fine particles of unelectrolyzed salt which may be present in the liquor. A procedure such as described is highly effective in remov-

ing impurities from caustic liquors, the resulting liquor being clear and water-white and having an exceedingly small iron content. In lieu of mixing fiber with the liquor and then separating the fiber from the liquor, a removal of the impurities may be effected by passing the liquor through one or more masses of fiber, preferably in a relatively loose condition and maintained on a suitable perforated plate or wire cloth support, and designed to permit sufficient time of contact between the liquor and the fiber to effect the desired adsorption and removal of the colloidal coloring impurities from the liquor. In such case, too, the fiber removes substantially all the impurities present in the liquor by virtue of its high adsorptivity, much in the same way that coloring impurities are removed from unrefined sugar solutions by passing the solution through bone charcoal. The fiber also serves to catch any mechanical impurities which may be present in the liquor, and other than being mercerized undergoes practically no reaction with the liquor.

While the process of the present invention is particularly useful in removing impurities from concentrated caustic liquors, it may also be applied to advantage in removing coloring impurities from caustic liquors of lower strengths, for example, those employed in soda and kraft pulp manufacture. In such case, the causticized smelt solutions are likely to be more or less turbid, and to contain colored colloidal impurities as a result of the smelting and causticizing operations. These may readily be decolorized by the process of the present invention, to yield clear white liquors eminently suitable for the production of high grade pulps.

Having thus described certain embodiments of this invention, it is evident that various changes and modifications might be made therein without departing from the spirit or scope of invention as defined in the appended claims.

I claim:

1. A process of decolorizing caustic liquor containing colloidal coloring impurities, which comprises contacting such liquor with fiber consisting substantially only of alpha cellulose, until such fiber has adsorbed substantially all the coloring impurities therefrom.

2. A process of decolorizing strong caustic liquor containing colloidal coloring impurities, which comprises uniformly mixing such liquor with fiber consisting substantially only of alpha cellulose, until such fiber has adsorbed substantially all the coloring impurities therefrom.

3. A process of decolorizing strong caustic liquor containing colloidal coloring impurities, which comprises uniformly mixing such liquor with cellulose fiber capable of adsorbing the colloidal impurities therefrom sub-

stantially without forming organic reaction products, and removing the fiber from the decolorized liquor.

4. A process of decolorizing caustic liquor containing colloidal coloring impurities, which comprises passing such liquor through a mass of cellulose fiber consisting substantially only of alpha cellulose.

5. A process of decolorizing caustic liquor containing colloidal coloring impurities, which comprises mixing such liquor with about 1% by weight of fiber consisting substantially only of alpha cellulose, and then filtering the liquor free of fiber through a mass of such fiber.

6. A process of decolorizing caustic liquor containing colloidal coloring impurities, which comprises contacting such liquor with cellulose fiber consisting substantially only of alpha cellulose and which has been beaten to increase its adsorptive surface.

In testimony whereof I have affixed my signature.

GEORGE A. RICHTER.
